UNITED STATES PATENT OFFICE.

HARRY A. GRAY, OF MILWAUKEE, WISCONSIN.

CIGAR AND CIGARETTE HOLDER.

1,243,158.

Specification of Letters Patent. Patented Oct. 16, 1917.

Application filed March 19, 1917. Serial No. 155,719.

To all whom it may concern:

Be it known that I, HARRY A. GRAY, a citizen of the United States, and resident of Milwaukee, in the county of Milwaukee and 5 State of Wisconsin, have invented certain new and useful Improvements in Cigar and Cigarette Holders; and I do hereby declare that the following is a full, clear, and exact description thereof.

10 My invention relates to new and useful improvements in tobacco containers, more particularly to holders for cigarettes, cigars and the like.

The principal object of the invention is to 15 provide a holder from which cigarettes or the like may be ejected one by one as required by the user.

The invention is particularly well adapted 20 for use by motorists and others who cannot well use both hands for removing a cigarette or cigar from its casing without materially interfering with the operation of their machine. With this device the operator may readily remove one cigarette or cigar at a 25 time with only the use of one of his hands.

An additional object is to simplify and improve the efficiency and convenience of operation of devices of this character.

With the above and several other objects 30 in view the invention resides in the novel features of structure, combination and arrangement of parts which will be hereinafter more particularly described and claimed and shown in drawing wherein:

35 Figure 1 represents side elevation of my invention, parts of the device being broken away and in section to more clearly show the interior structure.

Fig. 2 is a top plan view of this improved 40 holder, and

Fig. 3 is a horizontal section taken on the plane of the line 3—3 of Fig. 1.

In its preferred embodiment as shown in the figures of the drawing the invention consists of a substantially rectangular casing or container 1 of a length dependent upon the length of the articles which are to be used therewith. In other words if the container is to be used for holding cigarettes, it is only 45 slightly longer than the usual length of such articles, but if cigars are to be contained therein it will be considerably longer.

The opposite ends of the container are 50 preferably flat and the upper end 2 has an opening 3 formed therein at one corner as clearly shown in Fig. 2. The opening is of

sufficient size to readily allow a single cigarette or cigar to be ejected therethrough. The top 2 is removable so that a supply of cigarettes or cigars may be placed in the 60 container when necessary and they will be prevented from falling through the opening 3, should the container become inverted, by a plurality of flexible and resilient fingers 4 which extend inwardly of the opening 3 65 from the arcuate wall 5. These fingers are preferably formed on one edge of an arcuate rubber strip 6 which is cemented to the under side of the top 2 as shown in Figs. 1 and 2.

The container is further provided with a 70 false bottom 7 spaced slightly above the bottom 8, the cigarettes or cigars being adapted to rest upon said bottom 7. The false bottom is provided with an opening 9 adjacent one corner, said opening being adapted to 75 align with the discharge opening 3 in the top 2 and to receive an off-set portion 10 of a spring actuated arm 11 which is disposed between the two bottoms 7 and 8 and fixed to one wall of the container. 80

The arm is preferably formed from a flat leaf spring of appropriate length, the off-set portion 10 thereof being remote from the end which is attached to the container. In other words this off-set portion is adjacent 85 the free end of the arm and is movable longitudinally of the container, or into and out of the opening 9. The opposite side of the container from that to which the arm is attached is provided with a slot 12 to slidably 90 receive an outwardly extending actuating finger formed on the free end of the arm 11.

From Fig. 1 it is obvious that the arm 11 is so attached to the wall of the container that the off-set portion 10 will have a tendency to be normally disposed within the opening 9. If moved to the dotted line position as shown in this figure and then released it will quickly fly back to this normal position. This movement of the free end 100 of the arm 11 is utilized to eject the cigars or cigarettes through the opening 3 one by one.

Although the operation of the device is readily evident from the drawing it may be 105 briefly described as follows: assuming that the driver of an automobile or the like desires to smoke a cigarette, in which case he holds the container 1 with its supply of cigarettes so that the opening 3 will be adjacent 110 his mouth. The container is also positioned so that its longitudinal axis will be sub-

stantially horizontal and the opening 3 at the bottom so one of the cigarettes will drop by gravity into alinement with the openings 3 and 9. The operator now moves the finger 5 13 until it is in its dotted line position as shown in Fig. 1. The release of this finger will forcibly eject a cigarette from the container, the inner end of said cigarette having been engaged with the off-set portion 10 10 of the arm. The cigarette will thus have been thrown out into the operator's mouth. When an additional cigarette is desired the container is again manipulated to bring a cigarette in alinement with the two openings 15 as before mentioned. As a result of this the operator's attention is not diverted from the running of his automobile or other work which he may be doing.

I claim:

- 20 1. A device of the class described comprising a container for elongated objects having a discharge opening in one end, a leaf spring in the container at the end remote from the discharge opening, one end 25 of the leaf spring being fixed to the wall of the container, the other end being free and adapted to be moved longitudinally of said container to eject one of said objects through the discharge opening.
- 30 2. A device of the class described comprising a container for elongated objects having a discharge opening in one end, the wall of the container adjacent the other end having a slot, a leaf spring disposed in the 35 container transversely thereof, one end being secured to the wall of the container opposite the slot thereof, the free end being projected through said slot to form a finger piece, said free end being movable longitudinally of said container to eject one of said objects through the discharge opening.
- 40 3. A device of the class described comprising a container for elongated objects having a discharge opening in one end, a

false bottom for said container, having an 45 opening alined with the discharge opening, a spring fixed to the wall of the container and having an off-set portion to extend through the opening in the false bottom to engage one of said objects and eject the 50 same through said discharge opening.

4. A device of the class described comprising a container for elongated objects having a discharge opening in one end and adjacent one corner, a false bottom for the 55 container adjacent the other end thereof, said false bottom also having an opening alined with the discharge opening, and a spring disposed between the false bottom and adjacent end of the container and secured at one end to the wall thereof, the other end of the spring extending through the opposite wall of the container, the intermediate portion of the spring being off-set to extend through the opening in the false 60 bottom.

5. A device of the class described comprising a container for elongated objects having a discharge opening in one end, one wall of the opening being arcuate, means adjacent 70 the other end for ejecting one of said objects through the opening, an arcuate rubber strip secured to the top of said container coincident with the arcuate wall of the opening therein and inwardly extending fingers 75 on the edge of said strip projecting into the discharge opening to prevent the removal of an object except when actuated by said ejecting means.

In testimony that I claim the foregoing 80 I have hereunto set my hand at Milwaukee, in the county of Milwaukee and State of Wisconsin, in the presence of two witnesses.

HARRY A. GRAY.
